MINING MACHINE

Morris P. Holmes, Claremont, N. H., assignor to
 Sullivan Machinery Company, a corporation
 of Massachusetts

Application March 29, 1930; Serial No. 440,089.
 Renewed January 24, 1933.

39 Claims. (Cl. 262—30)

This invention relates to improvements in mining machines and more particularly has reference to improved flexible feeding means for a coal mining machine of the continuous cutter, bottom 5 cutting type.

An object of this invention is to provide an improved coal mining machine. Another object is to provide an improved feeding mechanism for a coal mining machine. A further object is to 10 provide improved flexible feeding means for a coal mining machine of the continuous cutter, bottom cutting type. Still another object is to provide an improved variable ratchet feed for a coal mining machine. These and other objects 15 and advantages of this invention will, however, hereinafter more fully appear.

In the accompanying drawings there are shown for purposes of illustration two forms which the invention may assume in practice.

20 In these drawings,

Fig. 1 is a plan view of a coal mining machine having embodied therein the improved flexible feeding means.

Fig. 2 is a side elevational view of the machine 25 shown in Fig. 1.

Fig. 3 is an enlarged plan view of the front or feed end of the machine shown in Fig. 1 and illustrating the improved feeding means, parts being shown in horizontal section to illustrate structural details.

Fig. 4 is a transverse vertical sectional view taken substantially on line 4—4 of Fig. 3.

Fig. 5 is a detail transverse vertical sectional view taken on line 5—5 of Fig. 3.

35 Fig. 6 is a longitudinally extending vertical sectional view taken on line 6—6 of Fig. 3.

Fig. 7 is a horizontal sectional view taken on line 7—7 of Fig. 6.

Fig. 8 is a horizontal sectional view taken on 40 line 8—8 of Fig. 6.

Fig. 9 is a detail sectional view taken on line 9—9 of Fig. 3.

45 Figs. 10 and 11 are detail sectional views illustrating a portion of the clutch controlling mechanism, Fig. 10 being taken on line 10—10 of Fig. 11.

Fig. 12 is a transverse vertical sectional view taken substantially on line 12—12 of Fig. 3.

50 Fig. 13 is a view similar to Fig. 3 showing a modified form of construction.

In the illustrative construction, as shown in the drawings, the improved flexible feeding means is embodied in a coal mining machine of the continuous cutter, bottom cutting, longwall 55 type although it is evident that the various novel

features thereof may be incorporated in coal mining machines of various other types. The mining machine generally comprises a machine frame 1 of generally rectangular shape having a plane bottom surface 2 on which the machine is slidably supported for movement over the mine bottom. As is usual in longwall mining machines, pivotally mounted on the rear end of the machine frame is an elongated plane cutter bar 3 supporting on its outer edges an endless cutter chain 4 carrying cutter bits 5. The cutter bar is swingable in a usual manner to positions at either side of the machine and lengthwise of the machine and a locking pin 6 carried by the cutter bar is provided for locking the bar in such positions. 70

In the present construction there is shown a feed operating member 7, herein a cable winding drum mounted for rotation about a vertical axis at the forward end of the machine frame although, if desired, the feed drum may be arranged in various other manners. Cooperating with the feed drum is a feed cable 8, while rotatable on upstanding axes at the opposite front corners of the frame are guide sheaves 9. The feed cable is adapted to be passed around these 80 guide sheaves and extended alongside the machine for attachment to the cutter bar to swing the bar about its pivot or to be extended, during the feeding operation, from the machine to a suitable anchor in a manner well known in the art. Housed within the machine frame is a motor 10 which herein may be of the reversible electric type having its power shaft 11 horizontally disposed and extending longitudinally of the machine. The cutter chain 4 is operatively 85 connected to the rear end of the motor shaft to any suitable transmission connection which herein may assume the form of those shown in my copending application Ser. No. 136,446, filed Sept. 20, 1926, patented July 21, 1931, Patent No. 1,815,872. The feed drum 7 is operatively connected to the front end of the motor shaft in an improved manner as hereinafter described. 90

In the preferred embodiment of the invention shown in Figs. 1 to 12 there is keyed to the rear end of the motor shaft 11 a spur pinion 12 meshing with a spur gear 13 rotatably supported on a horizontal longitudinally extending shaft 14 suitably journaled within the machine frame. The spur gear 13 is connectible to the shaft 14 by a multiple disc clutch 15. Also secured to the rear end of the motor shaft 11 is a spur pinion 16 meshing with an intermediate gear 17 (see Fig. 5) in turn meshing with a spur 100

105

110

gear 18. This spur gear is rotatably supported on the shaft 14 and is connectible to the shaft by a multiple disc clutch 19. It will thus be seen that upon alternative application of the friction clutches 15, 19, the shaft 14 may be driven in either of opposite directions. The improved operating means for these clutches will be later described. Keyed to the shaft 14 at the rear end thereof is a worm 20 meshing with a worm wheel 21 journaled as shown in Figs. 4 and 6 on a vertical shaft 22. This shaft is suitably journaled within the machine frame and the worm wheel is connectible to it by means including a clutch 23, as hereinafter described. Keyed to the lower end of the shaft 22 is a spur pinion 24 meshing with an internal gear 25 carried by the feed drum. It will be noted that in the present instance the feed drum 7 is journaled on bearings 26 supported by a vertical stud 27 midway between the sides of the machine frame and the feed drum is arranged in a chamber 28 extending transversely across the bottom portion of the machine frame and opening through the side walls of the latter so that the feed cable may be extended from the feed drum in various directions. In the illustrative construction shown, the worm wheel 21 (see Fig. 7) carries a plurality of spring pressed pawls 29 engageable with external ratchet teeth 30 formed on a ratchet sleeve 31 rotatably supported by the shaft 22. The jaw clutch 23 above referred to comprises clutch teeth 32 formed on the ratchet sleeve 31 and connectible by a shiftable clutch member 33 to clutch teeth 34 formed on a flange 35 integral with the shaft 22. The mechanism for shifting the clutch member 33 includes a pivoted shipper lever 36 connected by a link 37 to a reciprocable shaft 38 mounted within the machine frame. Secured to the outer end of this shaft is an operating handle 39. The shaft 38 may be shifted back and forth to effect swinging movement of the shipper lever, to move the clutch member into either its connected or released position. It will thus be seen that when the clutch 23 is connected and the worm wheel 21 is oscillated back and forth the shaft 22 is intermittently rotated through the ratchet and pawl mechanism in a direction to effect drive of the feed drum in winding direction at a relatively slow feeding speed. To prevent backward rotation of the feed drum 7 during driving thereof by said ratchet and pawl mechanism, there is provided a ratchet ring 35^a rotatably supported by a suitable bearing ring within an annular recess 36^a formed in the upper part of the worm wheel 21. The worm wheel has oscillatory movement relative to this ratchet ring and the latter is held stationary by means of a depending lug 37^a integral with the feed frame and having a rectangular portion fitting a rectangular opening 38^a in the ratchet ring 35^a. In the present construction, the ratchet ring 35^a carries a plurality of spring pressed pawls 39^a (see Fig. 8) which engage the ratchet teeth 30 formed on the ratchet sleeve 31. It will thus be seen that as the oscillatory worm wheel 21 effects drive, through the ratchet and pawl mechanism 29 and 30, of the feed drum in winding direction, the ratchet and pawl mechanism 30, 39^a prevents reverse rotation of the feed drum. The pawls 39^a prevent reverse rotation of the ratchet sleeve 31 as the pawls 29 slip over the ratchet teeth 30. Conversely, the pawls 39^a slip over the ratchet teeth 30 as the ratchet ring 31 is rotated by the pawls 29. Although the ratchet and pawl mech-

anism for preventing reverse rotation of the drum is carried within the worm wheel 21, it is obvious that it could be located in other positions, for instance so arranged as to engage ratchet teeth formed on the feed drum 7 itself. It will also be noted that any approved means may be provided for releasing the pawls 39^a at will to permit free rotation of the feed drum in unwinding direction. Disconnection of the clutch teeth 32 and 34 by downward movement of clutch member 33 will of course permit free rotation of the drum.

The mechanism for effecting oscillation of the worm wheel is associated with the operating mechanism for the friction clutches 15 and 19 and herein includes, in the preferred form of the invention, a worm wheel 40 journaled as shown in Fig. 4 on a vertical stud 41 and meshing with the worm 20. Secured to the upper surface of the worm wheel 40 is a guide member 42 having a radial guideway 43 and mounted within this guideway is a slide 44 carrying a crank pin 45 having its axis vertically disposed. The crank pin 45 may be adjusted toward or from the axis of the worm wheel to vary its throw and may be secured in any of its adjusted positions by a clamping bolt 46. Connected to the crank pin 45 is a link or connecting rod 47. As shown in Fig. 3, this connecting rod is outwardly bent at 48 to clear the spur gear 18 and is pivotally connected at 49 (see Fig. 10) to a member 50. The ends of the member 50 have upstanding perforated ears or lugs 51 and passing through the openings in these lugs is a horizontal bolt or guide pin 52. Slidably connected at 53 to this bolt 52 is a shipper arm 54. Interposed between the opposite sides of this arm and the lugs 51 and surrounding the bolt 52 are coil springs 55. It will thus be seen that the member 50, the bolt 52 and the coil springs form a resilient or yielding connection between the connecting rod 47 and the pivoted shipper arm 54 for the friction clutches. As shown in Figs. 3 and 12, the shipper arm 54 is pivoted at 56 within the machine frame and is equipped with rollers 57 engageable with plane surfaces of cylindrical clutch applying plates 58 and 59 for the friction clutches 15 and 19 respectively as shown in Fig. 3. As illustrated, the outer end of the shipper arm 54 is provided with inclined or rounded converging surfaces 60 and 61 and engageable with these surfaces is a spring pressed plunger 62 guided within a bore formed in a plate 63 secured to the inner side wall of the machine frame. This plunger is provided with a conical end 64 engageable with the inclined surfaces 60 and 61 and the tension of its spring 65 may be regulated by an adjustable cap plate 66 threadedly connected to the plate member 63 as clearly shown in Fig. 11. It will thus be seen that the shipper arm 54 has no central or neutral position, the conical end of the plunger 62 engaging the inclined converging surfaces 60, 61 on the shipper arm, always maintaining the latter in one or the other of its operative positions to apply one or the other of the friction clutches. It will therefore be evident that one or the other of the friction clutches 15, 19 is always applied and that upon rotation of the motor shaft 11 the worm 20 is rotated in one direction or the other, thereby effecting rotation of the worm wheel 40 to move the connecting rod and shipper arm to effect application of the other clutch. Therefore, the worm 20 is oscillated back and forth, the worm wheel 40, connecting rod 47, resilient connection between the connecting rod, and the ship-

per arm forming a trip-motion device to effect application and release of the friction clutches at timed intervals, thereby effecting oscillation of the worm wheel 21 which drives, through the ratchet mechanism described above, the feed drum. Upon adjustment of the crank pin 45 toward or from the axis of the worm wheel 21 the throw thereof, and resultantly, the rate of rotation of the feed drum, may be varied.

In the modified form of construction shown in Fig. 13 there is shown keyed to the rear end of the motor shaft 11, a spur pinion 70 meshing with a spur gear 72 secured to a horizontal shaft 73. This shaft extends longitudinally of and is suitably journaled within the machine frame and has keyed thereto at its rear end a bevel pinion 74 meshing with reverse bevels 75 and 76. These bevel gears rotate in opposite directions and are alternatively connectible by multiple disc clutches 77 and 78 to a horizontal shaft 79 extending transversely of and suitably journaled within the machine frame. Suitably secured to the shaft 79 is a worm 80 meshing with the worm wheel 21 and driving through the connections described above, the feed drum 7. The worm wheel 21, ratchet and pawl devices and jaw clutch 23 and the other elements above referred to are in this form of the invention arranged at one side of the central longitudinal vertical plane of the machine, the construction otherwise being the same as that in the preferred form. As illustrated, keyed to the hub of the bevel gear 76 and rotatably mounted on the shaft 79 is a sleeve 81. Rotatably mounted on this sleeve is an eccentric or cam member 82 and this member is connectible to the sleeve by a jaw clutch 83. Mounted on and surrounding the eccentric 82 is a ring-like member 84 having threadedly connected thereto a rod 85. This rod is pivoted as by a horizontal pin 86 to a member 87 which is in turn rotatably connected as at 88 to an operating rod 89, the latter being slidably guided within upstanding bearing brackets 90 suitably carried within the machine frame. Threadedly connected to the rod 89 at 91 is an adjustable nut member 92 while connected to the outer end of this rod, through a pin and slot connection 93, is an operating handle 94 and this pin and slot connection permits reciprocation of the rod 89 relative to the handle while permitting rotation of the rod by the handle. Pivotaly connected at 95 to the nut member 92 is a link 96 in turn pivotaly connected at 97 to a pivoted shipper arm 98 engaging a clutch applying member 99 interposed between the clutches 77, 78 and slidably mounted on the shaft 79. As shown in Fig. 13, a resilient or yielding pivotal mounting is provided for the shipper arm 98 and herein includes a plunger member 100 to which the shipper arm 98 is pivotally connected at 101. This plunger is provided with opposed shoulders engaging washers 102, in turn engaging abutment surfaces formed on the machine frame at the opposite ends of a chamber 103. Encircling the plunger member 100 and engaging the washers is a coil spring 104. It will thus be seen that the spring 104 is adapted to yield to permit movement of the plunger 100 in either direction. If it is desired to adjust the angular position of the shipper arm 98, this may be accomplished by grasping the handle 94 and rotating the same in the desired direction to adjust the nut member 92 relative to the operating rod 89. It will thus be seen that as the motor shaft is rotated, the reverse bevels are driven in opposite directions

and are alternatively connected to the shaft 79 through the trip-motion device including the eccentric 82, operating rod 89, etc., for the shipper arm 98 to effect oscillation of the worm 80. As in the preferred form described above, oscillation of the worm and worm wheel 21 is transmitted through the ratchet and pawl device 29, 30, it being understood that the jaw clutch 23 is connected, to the feed drum 7 to effect intermittent or step-by-step rotation of the latter in winding direction at a relatively slow feeding speed.

The general mode of operation of the improved mining machine will now be described. When the machine is positioned adjacent the coal face in the manner shown in Fig. 1, the feed cable 8 is extended from the feed drum 7 around the guide sheave 9 adjacent the coal face and forwardly along the inner side of the machine frame for attachment to the cutter bar. The cutter chain 4 and the feed drum 7 are then connected to the motor, and as the feed drum is slowly rotated, the feed cable 8 is wound in, thereby effecting swinging movement of the cutter bar from its mid-position to the full line position shown in Fig. 1, the cutter bar thereafter being locked by the pin 6 to the machine frame. The jaw clutch 23 is then released, disconnecting the feed drum from its drive and the feed cable is disconnected from the cutter bar and extended as shown in full lines in Fig. 1 from the feed drum around the guide sheave 9 adjacent the face and forwardly of the machine along the face of the coal to a suitable anchor. The clutch 23 is then again connected and the feed cable wound in by the feed drum, moving the machine bodily along the coal face to effect its cutting operation. These and other modes of use and advantages of the improved flexible feeding means will be clearly apparent to those skilled in the art.

As a result of this invention, it will be noted that an improved flexible feeding means is provided for a coal mining machine of the continuous cutter, bottom cutting type, the improved feeding means being relatively simple in construction and extremely flexible in operation. It will further be noted that the improved feeding means includes friction clutches which are automatically operated and controlled in an improved manner, thereby permitting drive through the improved ratchet device of the feed drum at a relatively slow cutting speed. It will still further be evident that by the provision of the improved trip-motion device operated by the gearing from which the feed drum is driven the reverse frictions are automatically applied and released.

While there are in this application specifically described two forms which the invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. A mining machine feeding mechanism including a feed operating member adapted to cooperate directly with flexible feeding means, and mechanism for driving said feed operating member in a direction to draw in its cooperating flexible feeding means including an oscillatory driving element and a driven element intermittently rotated in one direction, a motor, and

driving means for said driving element for positively oscillating the latter in opposite directions, said driving means being automatically intermittently connected in driving relation with 5 said motor and including a friction clutch and means for intermittently effecting and interrupting drive through said clutch.

2. A mining machine feeding mechanism including a feed operating member adapted to co- 10 operate directly with flexible feeding means, and mechanism for driving said feed operating member in a direction to draw in its cooperating flexible feeding means including a driven element intermittently rotated in one direction, a 15 motor, driving means for said driven element including an oscillatory element automatically intermittently connected in driving relation with said motor and a friction clutch through which said oscillatory element is driven, and means 20 for intermittently effecting and interrupting drive through said clutch for automatically effecting such connection at timed intervals.

3. A mining machine feeding mechanism including a feed operating member adapted to co- 25 operate directly with flexible feeding means, and mechanism for driving said feed operating member in a direction to draw in its cooperating flexible feeding means including a driven element intermittently rotated in one direction, a 30 motor, driving means for said driven element automatically intermittently connected in driving relation with said motor, and clutch means controllable by an element of said driving means 35 for automatically effecting such connection at timed intervals.

4. A mining machine feeding mechanism including a feed operating member adapted to co- 40 operate directly with flexible feeding means, and mechanism for driving said feed operating member in a direction to draw in its cooperating flexible feeding means including an oscillatory element, a motor, and driving means for said oscillatory element for positively moving the latter in opposite directions, said driving means 45 being automatically intermittently connected in driving relation with said motor and including a friction clutch, and means for intermittently effecting and interrupting drive through said clutch.

5. A mining machine feeding mechanism including a feed operating member adapted to co- 50 operate directly with flexible feeding means, and mechanism for driving said feed operating member in a direction to draw in its cooperating flexible feeding means including an oscillatory element, a motor, driving means for said oscillatory element for positively moving the latter in opposite directions, said driving means being 55 automatically intermittently connected in driving relation with said motor and including a friction clutch, and means for intermittently effecting and interrupting drive through said clutch for automatically effecting such connection at timed intervals.

6. A mining machine feeding mechanism including a feed operating member adapted to co- 60 operate directly with flexible feeding means, and mechanism for driving said feed operating member in a direction to draw in its cooperating flexible feeding means including an oscillatory element, a motor, driving means for said oscillatory element automatically intermittently connected in driving relation with said motor, and means driven by an element of said driving means 65

for automatically effecting such connection at timed intervals.

7. A mining machine feeding mechanism including a feed operating member adapted to co- 80 operate directly with flexible feeding means, and mechanism for driving said feed operating member in a direction to draw in its cooperating flexible feeding means including a step by step speed reducing device including an element movable in opposite directions, a motor, driving 85 means for said speed reducing device for positively moving said element in opposite directions, said driving means being automatically intermittently connected in driving relation with said motor and including a friction clutch, and means 90 for intermittently effecting and interrupting drive through said clutch.

8. A mining machine feeding mechanism including a feed operating member adapted to co- 95 operate directly with flexible feeding means, and mechanism for driving said feed operating member in a direction to draw in its cooperating flexible feeding means including a step by step speed reducing device including an element movable in opposite directions, a motor, driving means for 100 said speed reducing device for positively moving said element in opposite directions, said driving means being automatically intermittently connected in driving relation with said motor and including a friction clutch, and means for intermittently effecting and interrupting drive through 105 said clutch for automatically effecting such connection at timed intervals.

9. A mining machine feeding mechanism including a feed operating member adapted to co- 110 operate directly with flexible feeding means, and mechanism for driving said feed operating member in a direction to draw in its cooperating flexible feeding means including a step-by-step speed reducing device, a motor, driving means for said 115 speed reducing device automatically intermittently connected in driving relation with said motor, and means driven by an element of said driving means for automatically effecting such connection at timed intervals.

10. A mining machine feeding mechanism including a feed operating member adapted to co- 120 operate directly with flexible feeding means, and mechanism for driving said feed operating member in a direction to draw in its cooperating flexible feeding means including a ratchet and pawl device, a motor, and driving means for said ratchet and pawl device for positively moving the pawl thereof back and forth, said driving means 125 being automatically intermittently connected in driving relation with said motor and including a friction clutch, and means for intermittently effecting and interrupting drive through said clutch.

11. A mining machine feeding mechanism including a feed operating member adapted to co- 130 operate directly with flexible feeding means, and mechanism for driving said feed operating member in a direction to draw in its cooperating flexible feeding means including a ratchet and pawl device, a motor, driving means for said ratchet and pawl device for positively moving the pawl thereof back and forth, said driving means being 135 automatically intermittently connected in driving relation with said motor and including a friction clutch, and means for intermittently effecting and interrupting drive through said clutch for automatically effecting such connection at timed intervals.

12. A mining machine feeding mechanism including a feed operating member adapted to co- 140

150

- operate directly with flexible feeding means, and mechanism for driving said feed operating member in a direction to draw in its cooperating flexible feeding means including a ratchet and pawl 5
- 5 device, a motor, driving means for said ratchet and pawl device automatically intermittently connected in driving relation with said motor, and means driven by an element of said driving means for automatically effecting such connection at 80
10 timed intervals.
13. A mining machine feeding mechanism including a feed operating member adapted to cooperate directly with flexible feeding means, and mechanism for driving said feed operating member in a direction to draw in its cooperating flexible feeding means including a driven element intermittently rotated in one direction, a motor, and driving means for said driven element automatically intermittently connected in driving relation with said motor and including friction 85
15 clutch devices for alternatively effecting such connection and means for alternatively applying said clutch devices, one device always being released when the other is applied.
14. A mining machine feeding mechanism including a feed operating member adapted to cooperate directly with flexible feeding means, and mechanism for driving said feed operating member in a direction to draw in its cooperating flexible feeding means including a driven element intermittently rotated in one direction, a motor, driving means for said driven element automatically intermittently connected in driving relation with said motor and including friction clutch 90
20 devices for alternatively effecting such connection, and means for automatically effecting such connection at timed intervals including means for alternatively applying said clutch devices, one device always being released when the other is applied.
15. A mining machine feeding mechanism including a feed operating member adapted to cooperate directly with flexible feeding means, and mechanism for driving said feed operating member in a direction to draw in its cooperating flexible feeding means including a driven element intermittently rotated in one direction, a motor, driving means for said driven element automatically intermittently connected in driving relation with said motor and including friction clutch 95
25 devices for alternatively effecting such connection, and means for automatically effecting such connection at timed intervals including means for alternatively applying said clutch devices, one device always being released when the other is applied.
16. A mining machine feeding mechanism including a feed operating member adapted to cooperate directly with flexible feeding means, and mechanism for driving said feed operating member in a direction to draw in its cooperating flexible feeding means including a driven element intermittently rotated in one direction, a motor, driving means for said driven element automatically intermittently connected in driving relation with said motor and including friction clutch 100
30 devices for alternatively effecting such connection, and means driven by an element of said driving means for automatically effecting such connection at timed intervals.
17. A mining machine feeding mechanism including a feed operating member adapted to cooperate directly with flexible feeding means, and mechanism for driving said feed operating member in a direction to draw in its cooperating flexible feeding means including reversely rotatable elements, a driven element intermittently rotated in one direction, a motor operatively connected 105
35 to said reversely rotatable elements, and driving means for said driven element automatically alternatively connectible to said reversely rotatable elements.
18. A mining machine feeding mechanism including a feed operating member adapted to cooperate directly with flexible feeding means, and mechanism for intermittently driving said feed operating member, in a direction to draw in its cooperating flexible feeding means, at a substantially constant feeding speed, including reversely rotatable elements, an oscillatory driven element, a motor operatively connected to said reversely rotatable elements, driving means for said oscillatory element automatically alternatively connectible in driving relation with said reversely rotatable elements, and a step by step speed reducing device driven by said oscillatory element and operatively connected to said feed operating member. 110
40
19. A mining machine feeding mechanism including a feed operating member adapted to cooperate directly with flexible feeding means, and mechanism for driving said feed operating member in a direction to draw in its cooperating flexible feeding means including driving elements rotatable in opposite directions, an oscillatory driven element, means for connecting automatically said driving elements alternatively in driving relation with said driven element to effect oscillation of the latter, and means for transforming the oscillatory motion of said driven element to an intermittent rotary motion. 115
45
20. A mining machine feeding mechanism including a feed operating member adapted to cooperate directly with flexible feeding means, and mechanism for driving said feed operating member in a direction to draw in its cooperating flexible feeding means including an oscillatory driven element, a motor, driving means for said driven element for positively moving the latter back and forth, said driving means being automatically intermittently connected in driving relation with said motor and including a friction clutch and means for intermittently effecting and interrupting drive through said clutch, and means for transforming the oscillatory motion of said driven element to an intermittent rotary motion. 120
50
21. A mining machine feeding mechanism including a feed operating member adapted to cooperate directly with flexible feeding means, and mechanism for driving said feed operating member in a direction to draw in its cooperating flexible feeding means including a driven element intermittently rotated in one direction, a motor, and driving means for said driven element including an oscillatory driving element automatically intermittently connected in driving relation with said motor and including a friction clutch, and means for intermittently effecting and interrupting drive through said clutch, said driving element being positively moved back and forth by said driving means. 125
55
22. A mining machine feeding mechanism including a feed operating member adapted to cooperate directly with flexible feeding means, and mechanism for intermittently driving said feed operating member in a direction to draw in its cooperating flexible feeding means, at a substantially constant feeding speed, including reversely rotatable elements, a driven element, a motor operatively connected to said reversely rotatable elements, driving means for said driven element automatically alternatively connectible to said reversely rotatable elements, and a step by step 130
60
- 70

- tween said shafts for effecting rotation of said driven shaft intermittently in opposite directions, means for automatically actuating said reversing mechanism at timed intervals, and a ratchet and pawl transmission mechanism driven by said driven shaft. 5
 33. A mining machine feeding mechanism including a feed operating member adapted to cooperate directly with flexible feeding means and mechanism for driving said feed operating member in a direction to draw in its cooperating flexible feeding means including a drive shaft, a driven shaft operatively connected to said feed operating member, reversing mechanism between 10 said shafts for effecting rotation of said driven shaft intermittently in opposite directions, and means for automatically actuating said reversing mechanism at timed intervals and actuated by said driven shaft. 15
 34. A mining machine feeding mechanism including a feed operating member adapted to cooperate directly with flexible feeding means and mechanism for driving said feed operating member in a direction to draw in its cooperating flexible feeding means including a drive shaft, a driven shaft, a clutch for effecting rotation of said driven shaft in one direction, a second clutch for effecting rotation of said driven shaft in the opposite direction, and means for automatically 20 connecting and releasing said clutches at timed intervals to effect intermittent rotation of said driven shaft in opposite directions and including clutch actuating means driven by said driven shaft. 25
 35. A mining machine feeding mechanism including a feed operating member adapted to cooperate directly with flexible feeding means, and mechanism for driving said feed operating member in the direction to draw in its cooperating flexible feeding means including an oscillatory gear, connections between said gear and said feed operating member including an intermittent speed reducing device, a motor, and mechanism driven by said motor for automatically oscillating 30 said gear. 45
 36. A mining machine feeding mechanism including a feed operating member adapted to cooperate directly with flexible feeding means, and motor operated driving means for said feed oper- 50
 ating member including a control clutch, and mechanism controlled by an element of said driving means for automatically applying and releasing said clutch at timed intervals including a yieldable clutch shipper mechanism yieldable 80 upon overload of said clutch. 55
 37. A mining machine feeding mechanism including a feed operating member adapted to cooperate directly with flexible feeding means, and motor operated driving means for said feed operating member including a control clutch, and mechanism controlled by an element of said driving means for automatically applying and releasing said clutch at timed intervals including a yieldable clutch shipper mechanism yieldable 85 upon overload of said clutch, and means for increasing or decreasing the length of said intervals to vary the feeding speed. 90
 38. A mining machine feeding mechanism including a feed operating member adapted to cooperate directly with flexible feeding means, and motor operated driving means for said feed operating member including intermeshing worm gear elements, and means for intermittently actuating said worm gear elements including a controlling clutch through which power is transmitted to effect rotation of said gear elements, and mechanism for alternatively applying and releasing said clutch automatically during drive of 100 said elements including an actuating element rotatable with one of said gear elements. 105
 39. A mining machine feeding mechanism including a feed operating member adapted to cooperate directly with flexible feeding means, and motor operated driving means for said feed oper- 110 ating member including intermeshing worm gear elements, and means for intermittently actuating said worm gear elements including a controlling clutch through which power is transmitted to effect rotation of said gear elements, and mechanism for alternatively applying and releasing said clutch automatically during drive of 115 said elements including an actuating element rotatable with one of said gear elements, said mechanism including adjusting means whereby the intervals between 120 the application and release of said clutch may be varied to vary the feeding speed. 125
